SHOPPING BAG

Robert C. Groh, St. Paul, Minn., assignor to
Walter H. Deubener, St. Paul, Minn.

Application May 1, 1933, Serial No. 668,803

5 Claims. (Cl. 229—54)

The present invention relates to a shopping bag, or folding basket.

An object of the present invention is to make an improved and simplified shopping bag.

5 In order to attain this object, there is provided, in accordance with one feature of the invention, a shopping bag formed of a single piece of paper folded to form a basket, and having corner folded portions aligned with the upper edge of a side 10 thereof, a flap being provided on the upper edge of the side wall to overlap said folded corner portions, and perforations through said corner portions and through said side wall and flap, a looped cord being passed through said perforations to anchor the parts in position and to form 15 a carrying handle.

These and other features of the invention will be more fully brought out in the following description and the accompanying drawing, 20 wherein:

Figure 1 is a view in perspective of a shopping bag embodying the present invention, the bag being shown in open, upright position.

Figure 2 is a view, also in perspective, of the 25 bag as it appears when folded for shipment, or when not in use.

Figure 3 is a plan view of half of a blank of paper having the edge portions cut and folded for assembly, and the paper scored along the 30 lines of fold; and

Figure 4 is a sectional view on the line 4—4 of Figure 1, a portion of the card handle being shown in dotted lines.

Referring to the drawing in detail, a blank 1, of 35 paper, has the edge portions thereof notched as at 2 to the depth of the desired hem 3, the hem being folded inwardly on all four edges of the blank. The paper is then scored along the dotted lines, as illustrated in Figure 3, so as to facilitate

40 folding the bag into its finished shape. A strip 5, of cardboard, is inserted under each of the hem 3, the hem being folded inwardly on all four edges of the blank. The paper is then scored along the dotted lines, as illustrated in Figure 3, so as to facilitate

45 folding the bag into its finished shape. A strip 5, of cardboard, is inserted under each of the hem 3, the hem being folded inwardly on all four edges of the blank. The paper is then scored along the dotted lines, as illustrated in Figure 3, so as to facilitate

50 folding the bag into its finished shape. A strip 5, of cardboard, is inserted under each of the hem 3, the hem being folded inwardly on all four edges of the blank. The paper is then scored along the dotted lines, as illustrated in Figure 3, so as to facilitate

55 4. These corner portions are then inserted be-

neath the flaps 3, which are again folded down over the upper edges of the corner portions, as shown in Figures 1 and 4, bringing the openings 9, 10, and 11 and 12, 13, and 14 into registry with the openings 6, 7, and 8, respectively, through the flaps 3, the cardboard strips 5, and the side walls 4.

One end of a handle cord 21 is then inserted from the outer side of the bag through the upper, aligned perforations, which are aligned with the perforations 6. The end of the cord is projected into the interior of the bag, as at 22, a distance sufficient to provide enough cord to tie the knot illustrated in Figure 4, and is then passed outwardly through the central group of openings, 70 aligned with the opening 7, as at 23, and is then passed inwardly through the lower group of openings, aligned with the opening 8, as at 24. The cord is then looped upwardly, as at 25, and the end thereof is passed beneath the loop 26 in the interior of the bag, and the end 27 is then passed beneath the looped portion 25, completing the knot. The cord is then looped over and the procedure is repeated with the other, or free end of the cord, to form the handles 21. A pull 80 on the handle 21 tends to bind the loop portion 26 against the portion 25, where it passes beneath the loop 26, and also, in case of any slippage of the cord above this point, the loop 25 binds on the end portion 27 of the cord, giving 85 a double grip on the cord, which, in combination with the sharp angles as the cord passes back and forth through the side walls, positively anchors the cord against slippage; a bag of this character, of comparatively heavy paper, with 90 fiber cord handles, having sustained a load within the bag of over fifty pounds. The carrying capacity, of course, varies with the weight of paper used.

The knots of the handles, in addition to providing a carrying support for the bag, anchor the corner members in position and transmit a part of the carrying stress down along the diagonal fold 17 to the corners of the bag, which materially strengthens the bag at these points, and also 95 secure the entire structure in properly folded position without the necessity for the use of glue or extraneous fastening means.

The end portion of the bag is folded inwardly along the lines 28, 29, and 30, as in common paper 105 bag construction, and the bottom is capable of being folded inwardly, as at 31, see Figure 2, which feature is also well known to the art.

The bag is simple in construction and easy to manufacture, and lends itself readily to either 110

hand or machine construction. There are no glued seams in the entire construction of the bag, which avoids the possibility of the bag opening up and spilling its contents, if carrying parcels therein on a damp or rainy day, and, furthermore, the bag is absolutely tight, since the edges of the inwardly folded corner portions are flush with the top of the bag, so that if the bag were constructed of water proof material, it would be absolutely water tight. This is a distinct advantage in case the bag is desired to carry bulk granular or powdered material.

The handles are easily applied and hold the entire bag in folded position. At the same time, as previously brought out, the fastening of the handles to the inwardly bent corner portions, transmits the strain down to the corners of the bag and makes an extremely strong construction. The fact that the handles hold the entire bag in assembled position, greatly simplifies the shipment of large orders, since the sheets for forming the bag can be shipped scored and hemmed, as shown in Figure 3, with the perforations punched therein, and the bags can be readily assembled with the handles at the point of shipment, the handles and reinforcing cardboard strips 5 being shipped separately. This is a very material factor in paper bag manufacture, since the bulk of folded shopping bags is considerably greater than the bulk of the paper blanks when shipped in this manner.

The inward folding of the corner portions of the blank provides smooth exterior side portions of the bag. The overlapping of the upper edges of these inwardly folded corner portions, with the hems of the side walls, together with the novel and effective handle arrangement, which carries a portion of the load stress down to the bag corners, provide a novel and serviceable shopping bag.

It is understood that the broad idea of folding a blank of paper in the general manner set forth herein to provide a receptacle is not new, since the same general manner of folding has been long applied to the making of cartons for bulk ice cream.

I claim:—

1. A shopping bag formed of a rectangular blank of sheet material, each of the corners thereof being folded inwardly to form a receptacle with side and end walls, said folded corners having the upper edges thereof adjacent the upper edges of said side walls, a hem carried by each of said side walls, said hem being folded inwardly to overlie the upper edges of said folded corner portions, and a looped carrying handle penetrating each of said side walls, said hem, and said folded corner portions to secure said handle to said bag and to transmit a portion of the weight thereof from said handle to said corner portions.

65

70

75

2. A shopping bag having a reinforced upper edge portion, two sets of vertically aligned openings, consisting of three each, through said reinforced upper edge portion on each side of said bag, a looped carrying handle formed of cord and secured to said bag by passing an end thereof through each of the upper of said sets of openings, thence back through the second set of said openings, thence back again through the third set of said openings, the end of said cord being carried up and passed beneath said cord between the upper and center of said openings, and again beneath said cord between the second and lowest of said openings to secure said handle to said bag. 80

3. A shopping bag formed of a rectangular blank of sheet material, each of the corners thereof being folded inwardly to form a receptacle with side and end walls, said folded corners having the upper edges thereof adjacent the upper edges of said side walls, a hem carried by each of said side walls, said hem being folded inwardly to overlie the upper edges of said corner portions, a cardboard reinforcing member positioned beneath said hem on each side wall to extend laterally over a portion of said folded corner portions, and a looped carrying handle penetrating each of said side walls, said hem, said corner portions, and said reinforcing member to secure said handle to said bag and to transmit a portion of the weight thereof from said handle to said corner portions and to said reinforcing member. 95

4. A shopping bag formed of a rectangular blank of sheet material having a notch in each of the corners thereof, and at each end of the side walls thereof, a hem folded inwardly around the margin of said blank to the depth of said notches, each of the corners of said blank being folded inwardly to form a receptacle with side and end walls, said folded corners having the upper edges thereof adjacent the upper edges of said side walls and beneath the hems of said side walls, and a looped carrying handle penetrating each of said side walls, said hems, and said folded corner portions to secure said handle to said bag and to transmit a portion of the weight thereof from said handle to said corner portions. 100

5. A shopping bag formed of a rectangular blank of sheet material, each of the corners thereof being folded inwardly to form a receptacle with side and end walls, a hem carried by each of said side walls, said hem being folded inwardly to overlie the upper edges of said folded corner portions, and a looped carrying handle penetrating each of said side walls, said hem, and said folded corner portions to secure said handle to said bag and to transmit a portion of the weight thereof from said handle to said corner portions. 110
